UNITED STATES PATENT OFFICE.

FLORENCE C. PULCIFER, OF PORT HURON, MICHIGAN.

DESIGN FOR A JAR-RUBBER.

SPECIFICATION forming part of Design No. 35,064, dated September 10, 1901.

Application filed May 18, 1901. Serial No. 60,942. Term of patent 14 years.

To all whom it may concern:

Be it known that I, FLORENCE C. PULCIFER, a citizen of the United States, residing at Port Huron, in the county of St. Clair and State of Michigan, have invented and produced a new and original Design for Jar-Rubbers, of which the following is a specification, reference being had to the accompanying drawings, forming part hereof.

Figure 1 is a plan view of the jar-rubber. Fig. 2 is a transverse sectional view of the jar-rubber.

As shown in the drawings, the leading feature of my design consists of the annular portion 1, the inner edge of which describes a circle. On the outer edge of the annular portion 1 are located the imperforated lobes 2 2. The edge of each lobe 2 describes a semicircle. The outer edge of the annular portion 1 between the lobes 2 2 describes the arc of a circle concentric with the circle described by the inner edge of said portion. The center of the arc of the edge of each lobe is located at a point in line with the arc of the outer edge of the portion 1. The lobes 2 2 are arranged in two pairs, the two lobes of each pair being located diametrically opposite each

other, the diameters of the annular portion 1, upon which the pairs of lobes are arranged, extending at right angles to each other, the 30 said lobes being located on the outer edge of the annular portion at equal distances from each other, and if lines were drawn from the center of the arc of the edge of each lobe to the same center of the adjacent lobes the 35 four lines thus made would form a square the corners of which would be located on points in line with the arc of the outer edge of the annular portion 1. The annular portion 1 and the lobes 2 2 are all of the same 40 thickness throughout.

Having described my invention, what I claim as new, and desire to secure by Letters Patent, is—

The design for a jar-rubber as herein shown 45 and described.

In testimony whereof I have signed my name to this specification in the presence of two witnesses.

FLORENCE C. PULCIFER.
